UNITED STATES PATENT OFFICE.

MELISSA A. HAMMOND, OF HOPKINSVILLE, KENTUCKY.

MATCH FOLDER.

Application filed December 29, 1926. Serial No. 157,752.

This invention relates to an improved article of manufacture which I propose to entitle a match-folder.

Briefly, the invention has reference to a folder which is made from a card-board blank and folded into half sections, the longitudinal edge portions of which are constructed to permit them to be separably connected, and there being match retainers carried by

10 the inner faces of said halves.

My primary object is to produce an exceptionally handy contrivance of this character constructed with a view towards promoting low cost of manufacture and sale

15 while maintaining qualities desirable in an article of this character.

The specific structural features and advantages accruing therefrom will become more readily apparent from the following 20 detailed description and accompanying drawing.

In the drawings:—

Figure 1 is an exterior view of the folded article as it appears for pocket use,

Fig. 2 is an inside plan view showing the 25 internal match retainers,

Fig. 3 is an enlarged detail section.

In carrying out the invention I employ a cardboard blank of general rectangular configuration in top plan view. I provide this at its center with a fold line 2 dividing the blank into a pair of symmetrical half-sections or foldable halves 3 and 4. One longitudinal edge of the section 4 is notched out 30 as at 5 and provided with a finger-gripping tab as shown in Fig. 1. The longitudinal edge of the complementary section 3 is folded over against the inner side and terminates in an outwardly off-set retaining lip 6. This 35 allows the notched edge of the part 4 to be folded beneath the lip for maintaining the sections in folded condition. Attached to the inner central portions of the halves are

retainers 7 for the matches 8. I preferably employ two pairs of such retainers, there being a single pair for each half-section. Each retainer comprises a strip of corrugated paper board of desired resiliency which when glued or otherwise attached provides a multiplicity of open-ended cells for removable reception of the matches. It will be noted that the matches are arranged so that the heads are together. The matches are of course proportioned with respect to the retainers to allow the outer ends to protrude 45 a distance sufficient to permit them to be grasped for ready removal. By having the heads at the center they are prevented from becoming damp to a certain extent. Undoubtedly, by considering the disclosure 50 made in the drawings in connection with the explanatory description, a clear understanding of the invention as well as the advantages may be obtained. Therefore, a more 55 lengthy description is thought unnecessary. 60 Minor changes coming within the field of invention claimed may be resorted to if desired.

I claim:—

As a new product of manufacture, a match 70 folder comprising a cardboard blank folded between its ends to provide a pair of overlapping half-sections, the longitudinal outer edge of one section being folded over upon itself and terminating in a retaining lip, the 75 corresponding edge of the other section being adapted for disposition beneath said lip and being provided with a finger tab, and a plurality of pairs of corrugated match-holders secured to the inner faces of said half sections, the corrugations of each pair being in spaced relation and providing a plurality of match cells open at their opposite ends.

In testimony whereof I affix my signature.

MELISSA A. HAMMOND.
